UNITED STATES PATENT OFFICE

ADOLPH W. MACHLET, OF ELIZABETH, NEW JERSEY

BRASS-MELTING FURNACE

Application filed August 2, 1927. Serial No. 210,045.

This invention relates to improved means for melting brass.

Since the melting point of brass is extremely high, and since in order to make satisfactory brass castings, it is necessary to superheat the melted brass to about 2100° or 2200° so that it can be poured satisfactorily, it has been customary to use furnaces in which are embedded crucibles or melting pots formed of a composition of graphite or clay. These materials are poor conductors, and the cost of fuel mounts very high.

In aiming to economize heat, it has been the practice to employ many different sizes and forms of pots, for melting different quantities of brass, always using the smallest possible crucible for the work in hand. The crucible tends to soften and soon perishes from exposure to the extreme heat.

It is sought by the present invention to effect improvements in the construction and mounting of the crucible, to render it more efficient, to increase its durability, to facilitate the charging and discharging of the crucible, to facilitate, quicken and cheapen the melting of brass to bring the heat during the whole operation under more flexible and better control than has heretofore been found practicable, to make it practicable and economical to melt a small quantity in a large crucible, and to overcome other difficulties in brass melting.

If it is sought to melt the brass in an ordinary pot of metal, it is found that it cannot withstand high heat as successfully as a graphite crucible, and the danger is incurred that superheating of the brass in the metal pot would result in melting the metal pot itself. However, a metal pot or crucible is a desideratum because of its high conductivity and economy in fuel. According to the present invention, the brass is melted and superheated with less than half the expenditure of fuel than is necessary when using a graphite crucible. The difficulty and danger of melting the metal pot may be avoided by employing for the pot a wrought iron tube having ends of recalcitrant material, and keeping the tube in slow revolution, so that it cannot become over-exposed to heat at any

point, thereby avoiding melting or softening of the tube. The crucible may be made from a tube in the form of a barrel or hollow cylinder, which may extend in cumbent position for convenience in charging and discharging; and the flames may be applied to the top of the tube or barrel, whereby the top becomes heated and upon revolution reaches a bottom position, where it contacts with the deposited metal therein and melts the same. Owing to the conductivity of the tube, brass melting is effected economically. The crucible may be made of considerable length in proportion to its diameter, whereby the heat is utilized to the best advantage, inasmuch as a long thin body or heap of work-metal is more accessible to the heat and more readily melted, and a relatively long metal crucible of relatively small diameter is more efficient in melting the work-metal than is the standard relatively short metal pot of great diameter. The wrought iron tube has the advantage that it is not apt to amalgamate with the copper or the zinc of which the brass is formed.

The metal pot or crucible is preferably given the form of a bottle, and can be mounted for tilting, and it can be rotated on its longitudinal axis, and gas flames may be arranged to play upon the bottle as it rotates. Then it may be turned upon its trunnions to decant the melted brass; the crucible or bottle being mounted in a gas-furnace to tilt therewith, under the control of the operator. The wrought iron tube or the herein-described bottle may survive about twice as many heatings as an ordinary graphite pot; and when worn out it may be readily detached from its mountings and replaced by a fresh bottle.

The same crucible, because of its constant revolution, may economically melt either a large or a small quantity of brass. The invention is very flexible in meeting the different practical requirements, as compared with a graphite melting pot of standard manufacture.

The metal bottle is heated by means of a flame of mixed fuel-gas and compressed air, which is advantageously applied to the top portion of the revolving bottle, and substan-

tial reduction in the cost of brass melting is effected, as compared with standard brass-melting practice.

- The work may rest in the revolving crucible or bottle at a different portion thereof from the portion which is being exposed to the flame, the bottle being given a steady slow rotation upon its longitudinal axis, and the heat being applied at the upper portion of 5 the bottle remote from the work therewithin. The metal bottle absorbs the heat very readily, and by reason of its revolution it soon comes into contact with the work deposited therein and melts the same. Thus a metal 10 crucible may be employed in the form of a revolving pot or bottle, having a high degree of conductivity, as compared with standard graphite crucibles. This economy is rendered practicable by the rotation of the crucible, since the flame does not impinge long 15 enough against one point of the revolving bottle to melt or soften the same. This solves the problem of supplying heat to melt brass without melting the metal pot. While the revolution of the crucible prevents the same 20 from being exposed to the flame long enough at any one point to injure it, still it absorbs as much heat as is required, and imparts said heat to the brass work.
- 30 The wrought iron crucible may be prevented from internal oxidizing, and air or injurious gases cannot come in contact with the work, because the crucible is sealed. Internal pressure may be generated, which will 35 raise the boiling point of the melting brass, without raising the melting point thereof; that is, the pressure of the gas upon the work will be such that the vaporization point of zinc will be raised. The crucible is sealed at 40 its mouth so as to retain the volatilized zinc under pressure.

There must be an element used in the furnace as part of a heat-regulating device, as the furnace must be guarded very carefully 45 against overheating, which would result in the melting of the pot. The element is put into the bottom of the furnace below the retort where the flame cannot touch it. The difference is very slight between the melting 50 point of the pot and the point to which the melted brass has to be heated.

The bottle has a closed bottom from which extends a hub which is integral with the body of the bottle and projects through the wall 55 of the furnace.

At the other end the bottle is reduced in diameter and formed with a neck and mouth, the neck extending through a hole in the opposite wall of the furnace.

60 It will be understood that the use of a metal pot for brass melting has not heretofore been found feasible, because the brass has to be superheated after melting, and consequently the metal pot itself would be apt to 65 soften and melt from the heat; the melting

point of the metal pot being only a trifle higher than the point to which it is necessary to superheat the melted brass. It is moreover impracticable to guard against overheating a metal pot, under the circumstances. In addition, the metal of the pot would be apt to amalgamate with the brass, or with one of the constituents of the brass; and the amalgamation of the pot with the brass would lower the melting point of the 70 pot itself, so that melting of the material of the metal pot would be practically unavoidable. 75

It will be perceived that these difficulties 80 have been overcome by the present invention. One of the important features of the invention is the provision of means whereby the metal pot or crucible can be safeguarded against melting. To this end the heat is supplied to the pot or crucible at a point remote 85 from the point where the brass is being melted. The portion thereof that is pre-heated by the flames is slowly brought into contact with the brass, which is gradually melted and superheated. 90

It is further noted that the invention is not limited to the use of flames for heating the brass-melting bottle or canister, as the same may be otherwise heated. For melting a pound of brass, there needs to be used only 95 2½ cubic feet of fuel gas, which effects great economy. Quite a lot of metal is commonly lost by oxidation and evaporation. There is demand for a melter in which there will be a reduction of the loss of metal in melting, the 100 percentage of loss being very high according to previous practice. This loss is cut down substantially by the present invention. This invention keeps the quality of the melted 105 brass high. Parts 20 and 26 may be omitted 110 in some cases, without departing from the invention.

Other features and advantages will hereinafter appear.

In the accompanying drawings,

Figure 1 is a sectional elevation of a melting furnace taken longitudinally of the crucible.

Figure 2 is a sectional view of the crucible-barrel.

The scrap or metal to be melted is placed in a bottle-shaped crucible 10, which may then be in cumbent position. The crucible is heated by means of opposite burners 11, which burn compressed air and gas, said 115 burners opening into the top of a flame-chamber 12 forming part of the furnace 13, and the crucible is mounted to revolve within said flame-chamber, thereby exposing all portions of the crucible successively to the 120 burners; the capacity of the flame-chamber being such that the crucible almost entirely fills the same; the heavy furnace-walls 14 of fire brick or refractory material 15 serving 125 to confine the flames to the crucible, and also 130

aiding in heating the revolving crucible by inward radiation.

A crucible, if made of metal, is apt to develop trouble from itself tending to amalgamate with the melted brass therein. That is, there is a tendency of metal crucible-walls to alloy with the metal that is being melted. This trouble is largely due to the fact that the melting point of an alloy or amalgam (which tends to form between the work and the crucible) is much reduced compared with the melting point of the crucible alone, or as compared with the melting point of the work alone. In melting brass, it is necessary to deal with the very metal (zinc) that tends readily to dissolve or amalgamate with other metals. With a crucible made of wrought iron or low carbon steel, zinc will not readily combine or amalgamate, so that the difficulty is minimized or avoided by the use of wrought iron for the crucible.

The use of an ordinary alloy for the crucible would be found impracticable, because said alloy would be apt to amalgamate with the melting work. The melting point of the wrought iron crucible is about 2700° or 2800°, which is sufficiently high for practical purposes above the heat of 2200° to which the melted brass must be superheated before pouring. The melting point of brass is 1900°, but the melted brass has to be superheated up to 2100°, so that it can be poured successfully into moulds, because it is too sluggish for that purpose when it is barely melted. Sometimes the heat of the melted mass runs up to 2200°, or within 500° of melting the crucible itself. The difference is not great between the melting point of the crucible and the highest point to which it is necessary to melt the brass in order to pour it.

It will be understood that the use of a metal pot for brass melting has not heretofore been found feasible, because the brass has to be superheated after melting, and consequently the metal pot itself would be apt to soften and melt from the heat; the melting point of the metal pot being only a trifle higher than the point to which it is necessary to superheat the melted brass. It is moreover impracticable to guard against overheating a metal pot, under the circumstances. In addition, the metal of the pot would be apt to amalgamate with the brass, or with one of the constituents of the brass; and the amalgamation of the pot with the brass would lower the melting point of the pot itself, so that melting of the material of the metal pot would be practically unavoidable.

Heat control is rendered feasible by continually revolving the crucible, so that the portion thereof that is preheated by the flames is slowly brought into contact with the brass, which is gradually melted and superheated.

Wrought iron has sufficient strength so that

when the bottle is raised to the desired brass-melting heat, it will be self-supporting and maintain its form, and not be liable to soften so long as the bottle is revolving. This bottle is capable of use for over a hundred melting operations, as compared with about seventy for ordinary graphite crucibles. The metal has quite high conductivity, in that it readily absorbs the heat from the furnace, and readily imparts the same to the brass-work.

The rotation of the bottle prevents the flame from overheating and softening and perhaps melting, all of which might occur if the bottle were kept stationary, especially if flames were applied to the top thereof, as shown.

The wrought iron is made practically available by safeguarding it from the attack of the flames of the furnace by means of a tubular nickel jacket 16, which withstands the high heat and prevents access of oxygen to the exterior of the heated crucible, which, at the high heats employed in the melter, would cause the same to scale and become otherwise injured. The scale would tend to amalgamate with the furnace wall and effect substantial deterioration thereof. The crucible of wrought iron is then rendered practicable not only by heating it along one line or longitudinal portion and revolving it to melt the contained metal, but also by providing the crucible with a jacket of nickel or its equivalent. A tube of nickel or nickel alloy is a good conductor of heat, and it also excludes oxygen from attacking the exterior of the iron crucible and destroying the same, and withstands high heat, and is otherwise saving of the iron body of the retort. The nickel tube wall need be only about one-eighth of an inch in thickness. The interior of the bottle becomes coated with copper or brass, and does not scale.

The crucible or body of the bottle is entirely within the flame-chamber 12 of the furnace, although it has ends 18, 19 that extend beyond the walls of the furnace; the crucible-portion 10 being between the projecting ends of the revolving bottle.

Near one end the bottle is provided with a partition 20 which forms the dead end or bottom of the crucible, and the barrel-portion beyond the partition is filled with non-conducting or heat-resisting material 21. This projecting end 18 of the bottle is provided with circumferential grooving 22, 120 whereby it rides upon rolls 23 journaled upon the furnace end wall.

At the intake end, the crucible or bottle also projects from the furnace-walls at 19, and outside of the furnace-walls it rests upon rolls 24 that are mounted upon the other furnace end wall.

The bottom 20 of the bottle may be made of wrought iron or equivalent heat-resisting metal, and may be welded, as indicated at 130.

25. A wrought-iron crucible is thus made practicable, notwithstanding the high heats which are employed. To form a shoulder in the bottle, there is inserted in the bottle a 5 cone 26 made of wrought iron or its equivalent, which is also welded at 27 to the barrel. This cone or shoulder 26 may be steadied or supported by a wrought iron ring 28 exterior thereto, which fits within the contour of the 10 bottle and is also welded at 29 to the cone and may be welded to the bottle.

The crucible, if desired, may be in the form of a steel casting, and the casting may include the inner or bottom end or partition, 15 the neck and other parts. Wrought iron, however, is desirable, because it has a very high fusing point, and it resists the tendency to fuse with the work or contents of the crucible. This pure iron is preferable to 20 steel in most cases. Alloys are not found suitable for the body of the crucible, because alloys lower the fusing point at which the walls combine or amalgamate with the metal that is being melted.

25 The beak or shoulder 30 of the crucible is much reduced in diameter as compared with the diameter of the body. It is thus rendered practicable to tilt the crucible up a little from horizontal position while it is revolving, that is, to tilt the neck up and the bottom down. This makes it practicable to increase the charge of metal being melted, that is, to increase the capacity of the crucible. The furnace is swiveled upon horizontal trunnions 31, so that it may assume an inclined position, or in some cases a vertical or upstanding position, while the crucible may still be heated and also continued in revolution around its own longitudinal axis. The bottle may be swung to a vertical position, thereby still further increasing its capacity, because it will retain more molten metal or work when standing upright than when in a cumbent position. It may 45 be started horizontally, and afterwards tilted up to standing position, while still more metal is thrown in to be melted.

The crucible may be closed at both ends so that the gas produced from the melting and 50 vaporization of the work in the crucible will cause pressure, thereby raising the fusing point of the work in the crucible. A drive-wheel 32 for revolving the crucible is fastened upon this projecting end 18.

55 Between the wrought-iron shoulder of the bottle and the end of the bottle, the space 33 is occupied by a filling of plastic heat-resisting or refractory material 34, which has a tapering bore 35, being an outlet or forming 60 a neck which is larger at its outer end, and having its inner end coincident with and merging into the beak or shoulder 30 of the crucible. This lining or neck 34 of refractory material is used so that the melted metal, 65 when being discharged, may run over said

refractory material and hence will not lose an undue amount of heat to the same, and therefore will not become chilled or frozen. That is, the melted metal, while running out, is not apt to stick or adhere to the refractory material which forms the neck and mouth of the crucible, not even if the refractory material is cool.

At its open end the bottle is provided with a cover-disk 36, which is held on by releasable clamps 37. Within the tapering bore 35 of the bottle-neck fits a stopper or plug 38 of refractory material, which is secured on the inner side of said detachable cover 36.

75 The furnace-body is well insulated with end-segments 14 built up and an intermediate body 37^a of insulating material, which enclose the cylindrical body 38^a of the furnace, also of refractory material, said segments surrounded by a heat-conserving covering 39^a and by a metal sheathing 40. The sheathing or insulation may be silocel or any high quality of heat-resisting material, and is confined between the metal ends 41, 42 of the furnace, which is supported by its trunnions 31 upon a pair of uprights 43 between which the furnace is mounted, one of the trunnions having a segment 44 to mesh with an operating worm 45, whereby the furnace, together with the crucible, is tilted.

80 The mixed gas and air burners open into the constricted flame-chamber 12 above the crucible 10, where they are up out of reach of any melted metal that might escape from the crucible when old and worn out, so that the burners cannot become accidentally filled with melted metal. If the crucible should at any time give out at any point, the whole thing can be tilted up, and injurious results 85 minimized. A hole or drain can be made at 46 near the end of the flame-chamber 12, so that, in case of an accident, the melted metal escaping from the crucible can vent down and out through the hole. The melting can 90 be effected by other heating means.

95 The rear or bottom end of the bottle may be solid but preferably it has a central inlet 47 so that a central supply pipe 48 for gas may extend through the end into the bottle, to supply it with gas for some kinds of work, the pipe having a valve 49.

100 This inlet for gas into the bottom of the bottle can be used in some cases. When melting some metals, it may be desirable to introduce gas into the crucible, such as hydrogen or a compound of carbon or any gas, especially for its reducing effect, or for promoting the melting operation. Another advantage can be gained by introducing inert gas 105 under pressure, and that is that the fusing point of the work-metals can be raised without unduly increasing the heat of the crucible. In many cases, this inlet 48 for gas would not be needed, but it may be of use 110

except perhaps in cases where it is necessary to tilt the crucible up to a vertical position.

The heated walls of the furnace radiate a certain quantity of heat to the crucible, but, 5 the burners being placed over the top of the crucible, it results that the top is always heated a little hotter than any other part of the crucible, but is kept always in rotation. None of the work-metal or contents usually lies 10 at the top of the crucible, and hence there is nothing that would prevent the top from becoming highly heated, or even heated beyond the point required for melting the work, or perhaps softening or melting the bottle it- 15 self. That is, the crown is hottest. As the bottle revolves, the work-metal within the crucible comes in contact with the recently heated portion of the crucible, that is, when it reaches a bottom position, and thereby the 20 contents become heated and melted and no portion of the bottle is exposed to the flames for an undue period. The top of the crucible picks up the greatest heat because there is nothing in contact therewith to conduct 25 away the heat; but the heated top goes to the bottom during the revolution of the crucible, and the contents then absorb the heat.

The bottle may be used vertically or cumb- 30 rent. The burners 11 will work all right at the sides when the crucible is in vertical position, and the crucible will still rotate. It is used most of the time in cumbent position.

There is afforded a proportionately long 35 heating surface. If the scrap or work-metal is put into a standard crucible or melting pot, there is not afforded a maximum heating surface. In this novel proportionately long bottle, there is secured a quick result at greatly reduced cost for heating. The body of 40 metal scrap is long and thin, so that it is soon heated through, and it offers a great deal of surface for the heat to attack. Upon this principle the bottle is shaped, so that it is proportionately long, and the work-metal can 45 be melted much quicker and with the use of less powerful burners than would be the case with an ordinary melting pot.

The clamps 37 catch over a flange 50 which may be welded at 51 upon the tip of the bottle-neck. This flange is sufficiently small to permit the withdrawal of the bottle, when worn out, through the central main openings 52, 53 in the furnace ends; the supporting rolls 23, 24 being first taken down. These openings 55 52, 53 are as small as practicable, and of considerable length endwise of the retort, to minimize waste of heat from the flame-cham- ber.

The bottle may have a vent or an outlet 60 55 for gas, provided with valve and box at 54, permitting the bottle to be closed up.

The invention is not limited to the use of flames for heating the crucible, as it is well known practice to heat furnaces by electricity, 65 coal and oil, as well as gas.

Variations may be resorted to within the scope of the invention, and portions of the improvements may be used without others.

Having thus described my invention, I claim:

1. A brass-melter including a metal bottle including a barrel-portion at one end, a furnace including end walls through which the ends of the bottle project, heating means within the furnace, means for partitioning off the bottle from the projecting barrel-portion, said bottle having a shoulder at its other end, said shoulder having a neck terminating in a mouth and forming one of the projecting ends, means supporting said projecting ends for rotation, and rotating means connected to said bottle, said bottle being made of metal having substantially higher melting point than brass and not amalgamating with melted brass nor subject to scaling off where it is exposed to heat sufficient to melt brass. 70 75 80 85

2. The combination of a crucible forming part of a rotatable barrel, a furnace including end walls through which the ends of the barrel project, heating means within the furnace, means for partitioning off the crucible from the projecting ends of the barrel, means supporting said projecting ends for rotation, and rotating means connected to said barrel, said crucible being provided within said barrel 90 with a neck terminating in a beak, said barrel having outside of said beak an extension thereof formed of refractory plastic material, a cover for the end of the barrel, and a plug of refractory plastic material upon said cover 100 and closing the extension of said beak, the bore in said extension tapering from its outer end to its inner end. 95

3. A brass-melter including a shouldered brass-melting bottle having a reduced neck 105 terminating in a pouring mouth, and a furnace having a heating chamber in which the bottle is mounted for rotation and for decanting, said bottle being formed of wrought iron and having a protective casing of nickel suf- 110 ficient to prevent the wrought iron from scaling when heated to the brass-melting point.

4. A brass-melter including a brass-melting wrought-iron bottle jacketed with heat-resisting metal of higher melting point than 115 brass and having high heat conductivity, the jacketing not being subject to scaling off when exposed to brass-melting heat, said bottle closed at one end and provided at the other end with a shoulder ending in a neck pro- 120 vided with a pouring mouth, and releasable means spaced from said shoulder for closing the mouth of the bottle. 125

5. In a brass-melter, the combination of a metal tubular bottle of high heat conductivity, 125 capable of melting brass without amalgamating with the elements thereof, said bottle being liquid tight and having a shouldered portion opening into a neck provided with a mouth, a furnace having a heating chamber 130

in which the bottle is arranged and through the ends whereof the bottle projects for rotation, and burners arranged in the furnace along the bottle at one side thereof, the walls 5 of the furnace closely confining the bottle at other portions thereof, the burners operating along the top of the bottle, said bottle being of great length in proportion to its diameter, and being made of metal having substantially 10 higher melting point than brass and not subject to scaling off where it is exposed to heat sufficient to melt brass.

6. In a brass-melter, the combination of a 15 decantable metal bottle having a high melting point and high heat conductivity, a metal jacket protecting it from high heat, a furnace having a heating chamber in which the bottle is mounted for rotation, and burners arranged in the furnace along the bottle at 20 one side thereof, said burners arranged oppositely in a double row extending along the top of the heating chamber of the furnace, the flames entirely filling said heating chamber and said furnace having heavy walls of 25 fire brick and refractory material, said bottle closed at one end and having a pouring mouth at the other end, and packings of non-conducting material at both ends, and a removable closure for its pouring mouth.

30 7. The combination of a brass-melting wrought-iron bottle, a furnace having a heating chamber in which the bottle is mounted for rotation and decanting, said bottle having a shoulder and neck and pouring mouth 35 projecting from the furnace, and means to protect the wrought-iron bottle from attack by the heat of the furnace, said protecting means being a metal jacket of high conductivity, and having a higher melting point 40 than brass and not subject to scaling off when exposed to brass-melting heat.

8. A brass-melter having in combination a metal brass-melting bottle closed at one end and having a shoulder and a neck terminating 45 in a pouring mouth at the other end, and a furnace having a closed heating chamber in which the bottle is mounted for rotation, said chamber having means for supplying gas thereto, and a vent, and said bottle having a removable closure for its pouring mouth, said closure spaced from said shoulder and exterior to the furnace, and said bottle made of metal having substantially higher 50 melting point than brass and not amalgamating with melted brass nor subject to scaling off where it is exposed to heat sufficient to melt brass.

60 9. A brass-melter having in combination a liquid-tight metal bottle, and a furnace having a heating chamber in which the bottle is mounted for rotation, said bottle being wholly confined within the heating chamber of the furnace and having extending ends which project to the ends of the furnace, means supporting 65 said ends for rotation, said bottle and

said ends in the form of a tube, and said bottle having a shoulder, neck and mouthed portion in one end of said tube, and means closing the other end of said tube, said bottle formed of metal having substantially higher 70 melting point than brass and not amalgamating with melted brass nor subject to scaling off where it is exposed to heat sufficient to melt brass.

10. The combination of a crucible, a furnace having a heating chamber in which the crucible is mounted for rotation, said crucible being wholly confined within the heating chamber of the furnace and having extending ends which project to the ends of the furnace, said crucible and said ends in the form of a barrel, the extension of the barrel from the dead end or bottom of the crucible being filled with heat-resisting material, a disk of wrought iron being welded within the barrel to form the bottom or closed end of the crucible, and a cone-shaped annulus of wrought iron being welded in the opposite end of the barrel to form the neck of the crucible, and a wrought iron ring fitting within the barrel and supporting the neck.

11. The combination of a crucible forming part of a rotatable barrel, a furnace including end walls through which the ends of the barrel project, heating means within the furnace, means for partitioning off the crucible from the projecting ends of the barrel, means supporting said projecting ends for rotation, rotating means connected to said barrel, said crucible being provided within said barrel with a neck terminating in a beak, said barrel having outside of said beak an extension thereof formed of refractory plastic material, a cover for the end of the barrel, a plug of refractory plastic material upon said cover 100 and closing the extension of said beak, the bore in said extension tapering from its outer end to its inner end, said barrel, crucible end and neck being a single steel casting, a framework on the furnace, trunnions whereby the furnace is mounted upon the framework for 105 swinging, and mechanism for swinging the furnace upon said trunnions, said furnace having a main through which mixed air and gas are supplied under pressure to said flame-chamber, and said main having a flexible connection permitting the furnace to be tipped on its trunnions.

12. In a brass-melter, the combination of a 110 rotatable work barrel, a furnace including end walls through which the ends of the barrel project, heating means within the furnace, means for partitioning off the work chamber from the projecting ends of the barrel, the main portion whereof forms a bottle, 115 means supporting said projecting ends for rotation, and rotating means connected to said barrel, said furnace body formed of refractory material and surrounded with end segments of heat-resisting material, and an 120

- intermediate heavy cylindrical jacketing also of heat-resisting material, and having metallic end walls confining said material and also having a metallic tubular casing, the bottle 5 being decantable together with the furnace, and having at one end a pouring mouth within a projecting end of the barrel.
13. The combination of a crucible, a furnace having a heating chamber in which the 10 crucible is mounted for rotation, said crucible being wholly confined within the heating chamber of the furnace and having extending ends which project to the ends of the furnace, said crucible and said ends in the form 15 of a barrel, the extension of the barrel from the dead end or bottom of the crucible being filled with heat-resisting material, a disk of wrought iron being welded within the barrel to form the bottom or closed end of the crucible, and a cone-shaped annulus of wrought 20 iron being welded in the opposite end of the barrel to form the neck of the crucible, and a wrought iron ring fitting within the barrel and supporting the neck, the bottom or closed 25 end of the crucible having a central inlet for gas and a valve to control the gas.
14. In a brass-melter, the combination of a brass-melting bottle formed of highly conductive metal having a substantially higher 30 melting point than brass, and capable of being brought to brass-melting heat without scaling or softening, a furnace having a heating chamber in which the bottle is mounted, the furnace and bottle being decantable, 35 burners arranged in the furnace along the bottle at one side thereof, and means for rotating the bottle relatively to the burners, the bottle being closed at one end and having a shoulder, neck and pouring mouth at the 40 other end, the walls of the furnace closely confining the bottle at other portions thereof, the bottle being detachably mounted within the furnace so that when worn out it may be removed for replacement, and a removable 45 closure for the mouth of the bottle.
15. The combination of a crucible forming part of a rotatable barrel, a furnace including end walls through which the ends of the barrel project, heating means within the furnace, means for partitioning off the crucible 50 from the projecting ends of the barrel, means supporting said projecting ends for rotation, and rotating means connected to said barrel, said crucible being provided within said barrel with a neck terminating in a beak, said barrel having outside of said beak an extension thereof formed of refractory plastic material, a cover for the end of the barrel, and a plug of refractory plastic material upon 55 said cover and closing the extension of said beak, the bore in said extension tapering from its outer end to its inner end, said crucible having a vent for gas provided with a valve.
16. A brass-melter including a metal pot 60 in the form of a bottle having one end closed and the other end reduced for retaining the melted metal and provided with a pouring mouth at said reduced end, said bottle formed of metal of high heat conductivity, a furnace having a heating chamber in which the bottle 65 is mounted for rotation about its longitudinal axis and independently of the chamber, and burners arranged in the furnace along the bottle at one side thereof, the walls of the furnace closely confining the bottle at other 70 portions thereof.
17. A brass-melter having the combination of a metal bottle closed at one end, said bottle being shouldered at the other end, the shoulder having a neck provided with a 75 mouth, a furnace having a heating chamber in which the bottle is mounted for rotation, and burners arranged in the furnace along the bottle at one side thereof, the walls of the furnace closely confining the bottle at other 80 portions thereof, said bottle made of metal having substantially higher melting point than brass and not amalgamating with melted brass nor subject to scaling off where it is exposed to heat sufficient to melt brass. 85
18. A brass-melter including a metal pot in the form of a bottle having one end closed and the other end reduced for retaining the melted metal and provided with a pouring mouth at said reduced end, said bottle formed of metal of high heat conductivity, a furnace having a heating chamber in which the bottle is mounted for rotation about its longitudinal axis and independently of the chamber, and burners arranged in the furnace along the 90 bottle at one side thereof, the walls of the furnace closely confining the bottle at other portions thereof, said closed end and said pouring end each extending from the furnace and each provided with substantial packing 95 of non-conducting material, and each having means exterior to the furnace for supporting the bottle for revolution. 100
19. A brass-melter including a liquid-tight bottle mounted for decanting and closed at one end and having a shoulder, neck and pouring mouth at the other end, and a furnace having a heating chamber in which the bottle is arranged, said bottle being formed of wrought iron and having a protective casing 110 of nickel, and releasable means spaced from said shoulder for closing the bottle, said furnace having means arranged along one side of the bottle for heating the same, and closely confining the bottle at other portions thereof, 115 said bottle having an extension upon its bottom end, and both said neck and said extension projecting through the furnace walls and being exteriorly mounted for rotation. 120
20. A brass-melter including a brass-melting metal bottle closed at one end and having a shoulder which is provided with a neck having a pouring mouth at the other end and mounted for decanting the melted metal, a 125 releasable closure for the mouth of the bottle, 130

said closure spaced from said shoulder and exterior to the furnace, means for supplying gas under pressure to the interior of the bottle at the melting operation for the purpose set forth; and a furnace within which the bottle is mounted, said neck extending through the furnace wall to the exterior of the furnace and provided with a revoluble support, and means extending from the opposite end of the bottle through the furnace wall and provided with a revoluble support, and said bottle made of metal having substantially higher melting point than brass and not amalgamating with melted brass nor subject to scaling off where it is exposed to heat sufficient to melt brass.

21. The combination of a brass-melting wrought-iron bottle, a furnace having a heating chamber in which the bottle is mounted for rotation and decanting, said bottle having a shoulder and neck and pouring mouth projecting from the furnace, and means to protect the wrought-iron bottle from attack by the heat of the furnace, said protecting means being a metal jacket of high conductivity, and having a higher melting point than brass and not subject to scaling off when exposed to brass-melting heat, said furnace having a row of burners or heaters diametrically opposite from the pool of melted brass which gathers in the bottle, and the walls of the furnace closely confining said bottle throughout the remainder of its circumference.
